UNITED STATES PATENT OFFICE.

ALBERT ABBE GRISWOLD, OF PROVIDENCE, RHODE ISLAND, ASSIGNOR OF ONE-HALF
TO JOHN FRANCIS CHEVALIER, OF BROOKLINE, MASSACHUSETTS.

FLEXIBLE-SHINGLE MACHINE.

Application filed May 13, 1921. Serial No. 469,265.

To all whom it may concern:

Be it known that I, ALBERT ABBE GRISWOLD, a citizen of the United States, residing at Providence, in the county of Providence and State of Rhode Island, have invented a new and useful Improvement in Flexible-Shingle Machines, of which the following is a specification.

My invention has reference to an improvement in flexible shingle machines and more particularly to an improvement in a flexible shingle machine for manufacturing automatically flexible shingles such as is shown in my United States Patent No. 1,274,410, issued to me August 6, 1918.

The object of my invention is to improve the construction of such a flexible shingle machine, whereby a strip of flexible shingle material, two shingles wide, is fed into the machine intermittently and practically continuously, the strip of shingle material cut lengthwise and crosswise into shingles of the required size, the fastening wires formed and secured to the corners of two shingles simultaneously and the corners of two shingles with the fastening wires, bent over and onto the body of the shingles, simultaneously thereby forming undeturned flaps, with fastening wires, on the shingles and completing two shingles automatically, all in one operation of the machine.

My invention consists in the peculiar and novel construction and operation of a flexible shingle machine, said flexible shingle machine having details of construction, as will be more fully set forth hereinafter and claimed.

Figure 1 is a side view of my improved flexible shingle machine.

Figure 2 is a top plan view of the flexible shingle machine.

Figure 3 is a horizontal sectional view taken on line 3, 3 of Figure 1 looking down on the operating mechanism.

Figure 4 is an enlarged face view, partly in section, of one of the mechanisms for forming the wire fastener on the corner of a shingle.

Figure 5 is an enlarged side view of Figure 4, partly in section.

Figure 6 is an enlarged face view, partly in section, of one of the mechanisms for folding over the corner of a shingle onto the body of the shingle.

Figure 7 is an enlarged side view of Figure 6, partly in section.

Figure 8 is an enlarged face view, partly in section of the wire feeding mechanism.

Figure 9 is an enlarged face view, partly in section of the wire cutting mechanism.

Figure 10 is an enlarged detail transverse sectional view of the transverse shingle cutting mechanism taken on line 10, 10 of Figure 2.

Figure 11 is a plan view of the completed flexible shingle.

Figure 12 is an inverted plan view of the shingle.

Figure 13 is an enlarged transverse sectional view through the shingle, taken on line 13, 13 of Figure 12, and,

Figure 14 is a transverse sectional view through part of the wire feed mechanism, taken on line 14, 14 of Figure 8.

My improved flexible shingle machine consists essentially of the following elements, a frame, a driving mechanism, a feed mechanism, a longitudinal cutting mechanism, a transverse cutting mechanism, oppositely disposed wire forming and securing mechanisms, oppositely disposed wire feed mechanisms, oppositely disposed wire cutting mechanisms, and oppositely disposed shingle corner folding mechanisms.

In the drawings A indicates the frame, B the driving mechanism, C the feed mechanism, D the longitudinal shingle cutting mechanism, E the transverse shingle cutting mechanism, F, F, oppositely disposed fastening wire forming and securing mechanisms, G, G, oppositely disposed wire feed mechanisms, H, H, oppositely disposed wire cutting mechanisms, I, I, oppositely disposed shingle corner folding mechanisms of my improved flexible shingle machine, J a practically continuous strip of flexible shingle material K, K, wire and L the completed flexible shingle as shown in my previous patent.

The plan of the frame A is rectangular, it has the necessary bearings and openings for the different operative mechanisms, a flat bed 1 supported preferably on legs 2, 2 and having on each side of the bed raised longitudinal guide-ways 3, 3 for guiding the strip of flexible material J through the machine.

The driving mechanism B comprises a

transverse main driving shaft 4 rotatably supported in bearings in the frame A. The shaft 4 has bevel gears 5, 5, meshing with bevel gears 6, 6, on angular shafts 7, 7 supported in bearings from the bed 1. The shaft 4 also has a bevel gear 8 meshing with a bevel gear 9 on a shaft 10 in bearings on the side of the frame A. On the other end of the shaft 10 is a bevel gear 11 meshing 10 with a bevel gear 12 on a transverse shaft 13 supported in bearings in the frame A. On the shaft 13 are bevel gears 14, 14 meshing with bevel gears 15, 15 on angular shafts 16, 16 supported in bearings from the bed 1. 15 The layout of these driving shafts is shown in Figure 3 and they are for conveying power to the different operating mechanisms of the machine.

The feed mechanism C comprises a transverse lower feed roll 17 on a shaft rotatably supported in bearings in the frame A and extending through an opening in the bed 1. Over the feed roll 17 is a similar upper feed roll 18 on a shaft 19 in bearings on the bed 1 and on the shaft 19 is a ratchet 20. Pivoted on the shaft 19 is a lever 21 having on its upper end a pawl 22 engaging with the ratchet 20. On the lower end of the lever 21 is adjustably secured a connecting rod 23 which is adjustably and pivotally secured at its other end to a crank 24 secured to the main driving shaft 4 of the driving mechanism B, as shown in Figure 1. By this construction the strip of shingle material J is intermittently fed by the feed rolls 17 and 18 into the machine and onto the bed 1.

The longitudinal shingle cutting mechanism D consists of a thin central circular cutter 25 on a shaft 26 in bearings on the bed 1 and extending down through a slit in the bed 1. On one end of the shaft 26 is a sprocket wheel 27 operatively connected to a sprocket wheel 28 on the main driving shaft 4, by a sprocket chain 29, as shown in Figure 1. By this construction the strip of shingle material J is split lengthwise into two strips 30, 30 the width of a shingle.

The transverse shingle cutting mechanism E consists of a transverse cutting blade 31 having a lower cutting edge 32 working in conjunction with the sharp edge of a plate 33 embedded in the bed 1 at the edge of a transverse opening in the bed 1, as shown in Figure 10. The ends of the blade 31 are reciprocally supported in vertical guide standards 34, 34 on the bed 1. Each end of the blade 31 has a trunnion 35 to which is pivotally and adjustably secured the upper end of a connecting rod 36. The lower end of the connecting rod 36 is adjustably secured to an extension 37 on the main driving shaft 4, as shown in Figures 1 and 2. By this construction the blade 31 cuts the two strips 30, 30 65 of the shingle material transversely into two

square shingles at each operation of the machine.

Each of the oppositely disposed wire forming and securing mechanisms F, F are set at an angle on the bed 1 and extend transversely 70 over the corners of the shingles, as shown in Figure 2, in a position to insert, form and secure the fastening wires in the required place across the corner of the shingles. Each of these mechanisms consists of a lower staple forming and guide member 38 hung from the bed 1 and guiding vertically an upper staple forming block 39 and a lower pusher block 40. The upper block 39 has a roll 41 working in a cam groove 42 in a cam 43 on the shaft 7 to raise and lower the block. The upper forming block 39 also reciprocally supports a horizontal slide 44 having adjacent its rear end a notch 45 engaging with a continuous cam lip 46 on the periphery of the cam 43. The cam lip 46 is shaped to reciprocate the slide 44 in the block 39. The lower pusher block 40 has a roll 47 working in a cam groove 48 in a cam 49 on the shaft 7. On top of and secured to the bed 1 is a vertical guide standard 50 guiding vertically a lower presser block 51 and an upper forming block 52. A bell crank lever 53 having arms 54 and 55 is pivoted to a bearing 56 on the bed 1. The arm 54 has a slotted end 57 in which is a roll 58 on the back of the lower presser block 51. The arm 55 has a roll 59 on its lower end which works in a cam groove 60 in a cam 61 on the shaft 7. A bell crank lever 62 having arms 63 and 64 is pivoted to the bearing 56 on the bed 1. The arm 63 has a slotted end 65 in which is a roll 66 on the back of the upper forming block 52. The lower arm 64 has on its end a roll 67 working in a cam groove 68 in a cam 69 on the shaft 7. Toggle jointed arms 70 and 71 are pivotally secured together at their upper ends and to the upper forming block 52 and at the lower ends to the upper ends of wire forming arms 72 and 73 which are pivotally secured together at their lower ends and to the lower presser block 51, as shown in Figure 4. The wire forming arms 72 and 73 have in their outer edges 100 longitudinal wire grooves 74, 74, as shown in Figure 5 and the outer edges of these arms are shaped, as shown in Figure 4, to form the ends of the wire into the form as shown in Figure 13. The presser block 51 straddles the arms 72 and 73 so as to press the corner of the shingle down onto the bed 1, at each side of the place where a wire staple 75, as shown in Figure 5, is pushed through the corner of the shingle.

The cams and operating parts are constructed and timed so that the operations are as follows. The wire K is fed into the mechanism the distance required and the length required cut off as will be hereinafter 105 110 115 120 125 130

described. The cut off piece of staple wire now lays centrally across the opening in the top of the guide member 38, as shown in dotted lines in Figure 4. The forward end 5 of the slide 44 moving downwards over the wire, which is guided downwards in wire grooves 76, 76, in the guide member 38, forms the wire into a U shaped wire staple 75. On the upward movement of the lower 10 pusher block 40, the horizontal slide 44 recedes out of the way and in the next operation comes back over the next wire staple. The presser block 51 now moves down onto and presses the corner of the shingle L firmly 15 on the bed 1. The lower pusher block 40 on its upward movement pushes the arms of the wire staple 75 through an opening in the bed and through the corner of the shingle to their limit into the wire grooves 74, 74 20 in the wire forming arms 72 and 73, and simultaneously the upper forming block 52 moves downwards until the wire forming arms 72 and 73 are in a horizontal position, thereby forming the wire staple 75 into a 25 fastening wire 77, on the corner of the shingle, as shown in Figure 13.

Each of the wire feed mechanisms G, G consists of a hanger 78 hung from the bed 1, as shown in dotted lines in Figure 8. Pivoted to the lower end of the hanger 78 is a 30 lever 79 having a slotted upper end 80. A slide 81 having bifurcated arms 82, 82 is reciprocally supported in horizontal guide ways 83, 83 in the underside of the bed 1. 35 Pivoted between the bifurcated arms 82, 82 is a lever 84 having an upper off center wire biting end 85 and a lower end 86 on which is a transverse pin 87 in the slotted upper end 80 of the lever 79, as shown in Figures 40 8 and 14. On the lower end of the lever 79 is a roll 88 working in a cam groove 89 in a cam 90 on the shaft 7.

The forward movement of the slotted end 45 80 of the lever 79 moves the slide 81 and the wire K the distance of one fastening 40 wire by the biting end 85 of the lever 86 clamping the wire K between it and the slide 81. On the rearward movement of the end 80 of the lever 79 the biting end 85 is 50 free of the wire until the next revolution of the cam 90.

The wire cutting mechanism H consists of a blade 91 having a transverse cutting edge 92 and secured in the end of a recess 93 in 55 the underside of the bed 1. A pivot bearing 94 is secured to the underside of the bed 1. A cut off bell crank lever 95 is pivotally secured to the pivot bearing 94 and has a short 60 upper horizontal arm 96 to the end of which is secured a transverse blade 97 having a cutting edge 98 which with the cutting edge of the blade 91 cuts the wire K. The cut off bell crank lever 95 has a long lower arm 99 on the end of which is a roll 100 working in a

cam groove 101 in a cam 102 on the shaft 7. 65 The cam 102 is constructed and timed so that the wire K is cut at the time that the wire K is fed the distance required.

Each of the oppositely disposed shingle corner folding mechanisms I, I consists of a 70 pivot bearing 103 on the underside of the bed 1. A lever 104 is pivotally secured to the bearing 103 and has a straight lower arm 105 and a sickle shaped upper arm 106 working through an opening 107 in the bed 1. 75 The lower arm 105 has a U shaped end 108 with rolls 109, 109, on the ends of the arms of the U shaped end 108, which straddle the peripheral edge of a cam 110 on the shaft 16. 80 The peripheral edge of the cam 110 is shaped as shown in Figures 3 and 7 to swing the end of the sickle shaped upper arm 106 of the lever 104 through the opening 107 in the bed 1, at a predetermined time. On the top of the bed 1 is secured a pivot bearing 111 in which is a shaft 112. On the rear end of the shaft 112 is secured a shingle corner holding arm 113 which at a predetermined time extends across the corner of the shingle, on a line where the corner of the shingle is to be bent over, as shown in Figures 3, 6 and 7. On the forward end of the shaft 112 is secured a lever 114 having on its lower end a roll 115 working in a cam groove 116 in a cam 117 on the shaft 16. Secured to the top of the bed 1 is a pivot bearing 118 in which is a shaft 119. Secured to the rear end of the shaft 119 is an arm 120 having a slotted end 121. Secured to the top of the bed 1 is a standard 122 having 90 guide ways 123, 123 which guide vertically a presser block 124 over the corner of the shingle. On the back of the presser block 124 is a stud 125 working in the slotted end 121 of the arm 120. On the forward end of the shaft 119 is secured a lever 126 which extends through an opening in the bed 1 and has on its lower end a roll 127 working in a cam groove 128 in a cam 129, on the shaft 16. 95

The cams and operative parts are constructed and timed as follows. The shingle corner holding arm 113 comes down across the corner of the shingle where the corner is to be bent, as shown in Figures 6 and 7 and stays down until the end of the sickle shaped arm 106 has engaged with the corner of the shingle and raised the corner of the shingle into a nearly vertical position, when the arm 113 moves upwards out of the way, as indicated in dotted lines in Figure 7. The end of the sickle shaped arm 106 continues on over the bed 1 until the corner of the shingle is in the position as indicated in dotted lines in Figure 7, when the presser block 124 comes down and presses the corner of the shingle firmly against the body of the shingle, thereby completing the folding over of the shingle corner. The shingle corner 100 105 110 115 120 125 130

now forms an underturned flap 130 on the back of the shingle L, in which is the fastening wire 77, as shown in Figure 12.

The strip of shingle material J comes 5 from a source of supply, not shown, and goes through the machine underside up.

Each wire K comes from a source of supply not shown, and is fed into the machine at an angle, as described.

10 The operation of the different elements is as follows: With power applied to the pulley of the driving mechanism B, the strip of shingle material J is fed into the machine by the feed mechanism C and cut 15 lengthwise and crosswise by the longitudinal and transverse cutting mechanism D and E. The strip of shingle material and the cut off shingles are then held stationary and the fastening wire mechanisms F, F, the 20 wire feed mechanisms G, G and the wire cutting mechanisms H, H come into operation to put the fastening wire 77 into the corner of the shingle. The two forward shingles are now pushed along by the following shingles, the distance of one shingle, 25 on the next operation of the machine. The shingle corner folding mechanisms I, I now come into operation and fold the corners of the shingles onto the body of the shingles, 30 as described. As the shingles are completed they are pushed off the end of the bed 1 by the following shingles, into a receptacle or onto a conveyer, not shown. After the first 35 operation of the machine, the operations of putting the fastening wires into the corners of the shingles and folding over the corners of the shingles are done simultaneously. Each of the completed shingles L, L are the same as shown in my United States patent 40 referred to and the machine completes two of such shingles simultaneously and automatically, and one operator can tend to one or more of the machines.

Having thus described my invention I 45 claim as new:—

1. In a flexible shingle machine, a frame, a driving mechanism, means operatively connected with the driving mechanism for feeding a strip of flexible shingle material into 50 the machine, means operatively connected with the driving mechanism for cutting the strip of flexible shingle material into flexible shingles, means operatively connected with the driving mechanism for feeding wire 55 into the machine, means operatively connected with the driving mechanism for cutting a predetermined length from the wire and means operatively connected with the driving mechanism for inserting and forming 60 the length of wire into a fastening wire on the corner of a flexible shingle.

2. In a flexible shingle machine, a frame, a driving mechanism, means operatively connected with the driving mechanism for feeding flexible shingles in the machine, 65 means for intermittently feeding wire into

operatively connected with the driving mechanism for securing a fastening wire across the corner of a shingle and means operatively connected with the driving mechanism for folding over the corner of the shingle 70 onto the body of the shingle.

3. In a flexible shingle machine, a frame, a flat bed on the frame, a driving mechanism, means operatively connected with the driving mechanism for intermittently feeding a strip of flexible shingle material over the bed, comprising top and bottom feed rolls, a ratchet on one of the feed rolls, a lever pivotally secured in its operative position, a pawl on the lever engaging with the ratchet, a crank operatively connected with the driving mechanism, a rod adjustably connecting the lever with the crank, means operatively connected with the driving mechanism for cutting the strip of flexible shingle material lengthwise and means operatively connected with the driving mechanism for cutting the strips of flexible shingle material transversely into shingles. 80

4. In a flexible shingle machine, a frame, a flat bed, a driving mechanism, means for intermittently feeding flexible shingles over the bed, means for guiding the flexible shingles over the bed, means for intermittently feeding wire into the machine, means for cutting off a predetermined length of wire, means for forming the length of wire into a wire staple, means for forcing the arms of the wire staple through the corner of a shingle and means for forming the wire 90 arms into a fastening wire arm across the corner of the shingle. 95

5. In a flexible shingle machine, a frame, a flat bed on the frame, a driving mechanism, means for intermittently feeding flexible shingles over the bed, means for feeding wire into the machine, means for cutting off a predetermined length of wire, means for forming the length of wire into a wire staple, means for holding down the corner of a shingle, means for forcing the arms of the wire staple through the corner of the shingle and means for forming the wire into a fastening wire across the corner of the shingle. 105

6. In a flexible shingle machine, a frame, a driving mechanism, means operatively connected with the driving mechanism for feeding flexible shingles in the machine, means for intermittently feeding wire into the machine, means for cutting off a predetermined length of wire, and means for inserting the wire into the corner of a flexible shingle, as described. 110

7. In a flexible shingle machine, a frame, a bed, a driving mechanism, means for feeding flexible shingles over the bed, means for feeding wire into the machine, means for cutting off a predetermined length of wire, means for forming the length of wire into 120 125 130

a wire staple, means for holding down the corner of the shingle, means for forcing the arms of the wire staple through the corner of the shingle and means for forming the 5 wire staple into a fastening wire across the corner of the shingle, as described.

8. In a flexible shingle machine, having a bed, a wire forming and securing mechanism comprising a lower staple forming and 10 guide member hung from the bed, an upper staple forming block and a lower pusher block in the guide member, means for operating the staple forming block and means for operating the pusher block, a vertical 15 guide standard on the bed, a lower presser block in the guide standard, an upper forming block in the guide standard, means for operating the lower presser block, means for operating the upper forming block, toggle 20 jointed arms pivotally secured to the lower presser block and to the upper forming block and to each other and means on the toggle jointed arms for giving a predetermined shape to a wire, for the purpose as 25 described.

9. In a flexible shingle machine having a bed, a shingle corner folding mechanism comprising a shingle corner holding arm pivotally secured to the top of the bed and 30 adapted to cross the shingle where the corner is to be folded, means for operating the arm, a sickle shaped arm pivoted to the under side of the bed and working through an opening in the bed, to force the corner of 35 a shingle upwards, means for operating the sickle shaped arm, a standard on the top

of the bed and having guide ways, a presser block in the guide ways and means for operating the presser block, for the 40 purpose as described.

10. In a flexible shingle machine, the combination of the following instrumentalities, a frame, a driving mechanism B, shafts 7, 7, operatively connected with the driving mechanism B, a flexible shingle 45 feed mechanism C operatively connected with the driving mechanism B, a longitudinal flexible shingle material cutting mechanism D operatively connected with the driving mechanism B, a transverse flexible 50 shingle material cutting mechanism E operatively connected with the driving mechanism B, a fastening wire forming mechanism F operatively connected with the driving mechanism B, a wire feed mechanism G 55 operatively connected with the driving mechanism B, a wire cutting mechanism H operatively connected with the driving mechanism B and a shingle corner folding mechanism I operatively connected with the 60 driving mechanism B, whereby a strip of flexible shingle material is intermittently fed into the machine, cut lengthwise and crosswise into flexible shingles, fastening wires formed on and across the corners of 65 two shingles simultaneously and the corners with the fastening wires folded over onto the bodies of the two shingles simultaneously, as described.

In testimony whereof, I have signed my 70 name to this specification.

ALBERT ABBE GRISWOLD.
